UNITED STATES PATENT OFFICE

160,289

FRUIT PICKER

Ernest L. Wetzig, Clint, Tex.

Application January 9, 1948, Serial No. 143,627

Term of patent 3½ years

(Cl. D35—2)

To all whom it may concern:

Be it known that, Ernest L. Wetzig, a citizen of the United States and a resident of Clint, in the county of El Paso and State of Texas, have invented a new, original, and ornamental Design for a Fruit Picker, of which the following is a specification, reference being had to the accompanying drawings forming part thereof, in which:

Figure 1 is a front elevational view of a fruit picker showing my new design;

Figure 2 is a side elevational view.

Figure 3 is a bottom plan view, and

Figure 4 is a top plan view thereof.

I claim:

The ornamental design for a fruit picker, as shown.

ERNEST L. WETZIG.
